DESIGN FOR A VANITY CASE

Arthur P. Conant, Fort Thomas, Ky., assignor to
Lentheric Incorporated, New York, N. Y., a cor-
poration of New York

Application October 24, 1940, Serial No. 96,047

Term of patent 7 years

To all whom it may concern:

Be it known that I, Arthur P. Conant, a citizen of the United States, residing at Fort Thomas in the county of Campbell and State of Kentucky, have invented a new, original, and ornamental Design for a Vanity Case, of which the following is a specification, reference being had to the accompanying drawing, forming part thereof.

In the drawing:

Fig. 1 is a top plan view of a vanity case showing my new design;

Fig. 2 is an end elevational view thereof; and
Fig. 3 is a side elevational view thereof.

The characterizing feature of the design resides in the vanity case disclosed, having an external configuration such that its transverse section has a substantially semicircular end from which extend two straight, converging lines whose termini are joined by a re-entrant obtuse angle, substantially as shown.

I claim:

The ornamental design for a vanity case, substantially as shown and described.

ARTHUR P. CONANT.
